his ATTORNEY.

UNITED STATES PATENT OFFICE.

RALPH V. SAGE, OF WESTMONT BOROUGH, PENNSYLVANIA.

CAR-DOOR-OPERATING MECHANISM.

1,170,677.

Specification of Letters Patent.

Patented Feb. 8, 1916.

Application filed June 7, 1913. Serial No. 772,231.

To all whom it may concern:

Be it known that I, RALPH V. SAGE, a citizen of the United States, residing in the borough of Westmont, in the county of Cambria and State of Pennsylvania, have invented certain new and useful Improvements in Car-Door-Operating Mechanism; and I do hereby declare the following to be a full, clear, and exact description of the invention, such as will enable others skilled in the art to which it appertains to make and use the same.

My invention relates to improvements in railway freight car construction and more especially to the car door operating mechanism and the manner of mounting the operating shafts therefor.

One object of my invention is to provide center bearings for the operating shafts of car door mechanism well adapted to those of the hopper bottom type, which will be simple in construction, cheap to manufacture, light in weight, but of sufficient rigidity and strength to withstand the pressure, strain and shocks produced by the weight of the lading when dropped thereon, or in transit, or while discharging the lading from the car.

With these objects in view, I rivet, bolt or secure directly to the inner side of each inside hopper sheet, a rolled plate, each having a horizontally bent inturned integral flange along its upper edge, which is attached to the lower flange of each of the center sills of the car, thus forming a rigid connection between the inside hopper sheets and the center sills. Each bent plate projects downwardly below the edge of the hopper and has extending therethrough, a perforation, within which, the door operating shaft is journaled.

Another object of my invention is to increase the thickness of the curved upper end of the connecting lever or link which is swung over and extends beyond the operating shaft, when the doors are closed, with its end attached to the crank arm, whereby extra strength is secured where needed, and the increased weight of the end of said lever will aid in holding the doors more securely closed and prevent them from being accidentally opened.

Having thus given a general description of my invention, I will now, in order to make the matter more clear, refer to the one sheet of drawings accompanying this specifi-

cation and in which like characters of reference indicate like parts throughout the views.

Figure 1 is a vertical longitudinal sectional elevation through the center of a portion of a car, taken on the line I—I of Fig. 2. Fig. 2 is a vertical transverse section taken on the line II—II of Fig. 1 through the center of a car, looking in the direction of the arrows. Fig. 3 is a detail view showing a portion of a center sill and enough of the intermediate part of the hopper sheet to illustrate the position of the bearing plate member and the manner of attaching the same to the inner hopper sheet and the lower flange of the center sills of the car. Fig. 4 is a detail view showing the outside bearing casting for the outer end of the door operating shaft with the pawl, ratchet and locking dog mounted thereon, and a portion of the hopper casing on which it is secured.

Referring now to the various characters of reference on the drawings:—1 indicates the car door operating shaft having its outer bearing in a casting 2 riveted to the outside hopper sheet 3 and its inner end and intermediate portion mounted in bearings 4 and 5 respectively, which are attached to the inner side of each of the inside hopper sheets 6 at either side below the center sills 7. These inside hopper sheets 6 extend upwardly on either side of the center sills 7, their upper ends being preferably bent inwardly at an angle as shown, and to which the downwardly extending ends of the central ridge 8 of the car are riveted.

The bearing plate members 4 and 5 are each made of a flat rolled plate of substantially the same size and shape and are each provided with a flange 9 bent at right angles to the body of each plate along one side thereof, the corners of the bends, however, being slightly rounded, as shown.

The bearing plate members 4 and 5 are each attached vertically to the inner side of each of the inside hopper sheets 6 of the car next to the center sills 7 and extend rearwardly from the center of the car toward the end thereof beyond the lower edge of the hopper sheets, and each has a perforation in its extending portion as shown at 10, to form a journal bearing for the operating shaft 1. The flanges 9 of the upper edge of both the bearing plate members 4 and 5 are bent inwardly toward the longitudinal center of the car, forming right and left flanges,

and are riveted to the bottom flange of each of the center sills 7 respectively. In attaching the bearing plate members 4 and 5 to the inner hopper sheets 6 and to the center sills 7, in this manner a very efficient bearing member is produced, which, at the same time, forms a rigid connection between the center sills 7 and the hopper sheets 6 and further stiffens the car structure.

10 The operating shaft 1 has its inner end and intermediate portion journaled in the perforations 10 formed in the bearing plate members 4 and 5. Mounted centrally upon the operating shaft 1, between these two bearing members 4 and 5 and spaced apart by means of the tubular sleeves 11, and keyed, or otherwise rigidly secured to the operating shaft to prevent turning, is a crank arm 12 which is bifurcated at its outer end to receive the upper enlarged curved end 13 of a lever or connecting link 14 which is pivoted thereto by means of a pin connection 15, while the opposite end of the connecting link 14 is pivotally attached to 25 the door spreader bar 16 by means of eye bolts 17.

The outer end of the operating shaft 1, which is journaled in the casting 2 on the outside hopper sheet 3, extends beyond the same and is squared as at 18 to receive the ratchet wheel 19. A pawl 20 for engagement with the ratchet 19 and a locking dog 21 are pivoted on the casting 2 by means of which the operating shaft 1 is locked.

35 By forming the center bearings for the operating shaft as above described, very cheap and effective constructions are provided, the extra thickness and strength of the curved upper end 13 of the connecting link 14, which is thrown over the operating shaft when the doors are closed, assists in maintaining the doors closed, even if the locking mechanism at the outer end of the shaft becomes disarranged.

45 While I have shown and described my invention in considerable detail, I do not wish to be limited to the exact construction specified, but may use such substitutions, modifications or alterations as fall within the scope of my invention as set forth in the claims.

What I claim as new and desire to secure by Letters Patent is:—

1. A bearing plate member for a car door operating shaft, comprising a perforated flat rolled plate with a flange bent at right angles along one of its edges, said bearing plate member being riveted to the hopper sheet of the car with its flange attached to a sill of the car and forming a rigid connection between the center sill and the hopper sheet.

2. A center bearing for a car door operating shaft, comprising a perforated flat rolled plate riveted to the outside of the inner hopper sheet, a flange bent at right angles along the upper edge thereof riveted to the bottom flange of the center sill and forming a rigid connection between the center sill and the hopper sheet. 70

3. A center bearing for a car door operating shaft, comprising a flat rolled plate riveted to the inside hopper sheet of the car, the downwardly extending portion of same being perforated to receive the operating shaft, and provided with a flange bent at right angles to the perforated portion and riveted to the center sill of the car and forming a rigid connection between the center sill and the hopper sheet. 80

4. A center bearing for a car door operating shaft comprising a flat rolled plate riveted to the inside hopper sheet of the car and extending downwardly therefrom beyond the edges of the hopper, a perforation in said downwardly extending portion adapted to receive the operating shaft, and a flange bent at right angles to the said downwardly extending portion and riveted to the center sill of the car, thereby rigidly connecting the hopper sheet with the center sill. 90

5. In a railway car, a plurality of rolled plates attached to the inside hopper sheets and extending downwardly therefrom on either side of the center sills, perforations therein forming center bearings for the car door operating shaft, each of said plates having a flange bent at right angles to the downwardly extending portion and attached thereby to the lower flanges of the center sills and forming a rigid connection between the inside hopper sheets and the center sills. 100

6. In a railway car, a pair of rolled plates disposed one on each side of the center sills, attached to the inside hopper sheets and extending vertically downwardly therefrom longitudinally of the car, a perforation in each of said downwardly extending portions adapted to form bearings for the car door operating shaft, a horizontal flange formed at right angles along the top edge of each of the said pairs of rolled plates, said horizontal flanges being attached to the bottom flange of the center sills and rigidly connecting the hopper sheets with the center sills. 110

In testimony whereof I hereto affix my signature in the presence of two witnesses.

RALPH V. SAGE.
